UNITED STATES PATENT OFFICE.

WILLIAM E. WOODARD, OF FOREST HILLS, NEW YORK.

LOCOMOTIVE BUMPER DEVICE.

Application filed November 5, 1924. Serial No. 747,881.

This invention relates to bumpers such as are used in locomotives, and it has for one of its primary objects the provision of an improved arrangement whereby the liability of derailing and wrecking of the locomotive and train when the locomotive strikes an obstruction on the track, such for example as a modern motor truck is reduced to a minimum. Motor trucks have become so heavy and of such large capacity that more frequently than not in cases of collision the locomotive is derailed. If the truck is thrown down on the rails on impact, derailment is a practical certainty. My invention, therefore, aims to deflect the obstacle from off the track.

A more specific object of the invention is to provide means whereby existing bumpers can be readily adapted to realize the advantages of my invention.

How the foregoing together with such other objects as may hereinafter appear or are incident to my invention are obtained is illustrated in the accompanying drawings, 25 wherein

Fig. 1 is a plan view of one embodiment of my invention;

Fig. 2 is a front elevation of Fig. 1;

Fig. 3 is a side elevation of Fig. 1; and 30 Fig. 4 is a vertical section illustrating a detail of the invention.

Referring now to the drawings, the reference character A denotes the forward end of the locomotive structure which carries a bumper beam 7, which may well be the usual form of beam, although in this instance the beam is of special design in that it has wings 8-8 extending outwardly and rearwardly from the main body of the beam and formed integrally therewith. Such wings can be applied to some forms of standard beams.

In advance of the beam is a pilot B comprising a base portion 9, or pilot proper, from 45 which two spaced wings 10-10 rise, the whole piece being thus of substantially U-shape in vertical front elevation. The base is V-shaped in horizontal cross section so as to present a V-shaped front with the apex forward. The side members 10-10 are in an upward continuation of the sides of the base and are triangular in cross-section. The side members are secured to the beam by the bolts 11 and the base is secured to the 50 beam through the medium of the bracing

brackets 12-12 and also the bracing strap 12a. The pilot as a whole is thus of very strong construction, well supported and backed.

In the space between the legs 10-10 is arranged a coupler pocket casting C in which the shank of the coupler is pivoted. The pocket casting is secured to the beam and comprises an upper member or table 13, the upper face of which is in approximately the same plane as that of the side members 10-10 and that of the beam 7; the side walls 14-14; and the bottom wall 15; all parts being so formed that the casting has a very strong construction.

The pilot and the pocket casting cooperate to provide a V-front member in advance of the beam with a coupler pocket in the front. It will be observed, however, that apex of the table 13 and apex of the base 70 are in vertical alignment and that the horizontal depth of the pocket is such that coupler projects only far enough in advance of the line of the apices as to permit access to the pin 15 and to permit proper coupling. The coupler thus in reality cooperates with the other parts to present a V-front which, for all practical purposes, may be considered uninterrupted. The advantage of this 80 is that the coupler head, on collision with an obstacle will cooperate with the other parts to deflect the same and will not operate to throw the obstacle down on the track or act as an overhanging retaining ledge. In fact the coupler will prevent the table from acting as a retaining ledge. The wings 8-8 are a continuation of the side walls of the 85 V-front.

The device, while composite, is rigid and performs the desired functions. The pilot 95 and pocket can be applied to existing beams to provide a more effective bumper construction.

I claim:

1. A locomotive bumper construction comprising a bumper beam, and a coupler pocket and a pilot in front of the beam, the one above the other, the pocket and pilot together presenting a V-shaped substantially vertical 100 disposed front wall.

2. A locomotive bumper construction comprising a bumper beam, and a coupler pocket and a pilot in front of the beam, the one above the other, the pocket and pilot together presenting a V-shaped substantially vertical 110

ly disposed front wall, the bumper beam having side wings presenting surfaces in substantial continuation of the V-front wall.

3. A locomotive bumper construction comprising a bumper beam, and a pilot having a V-shaped lower portion with similarly disposed side members rising therefrom spaced, however, to accommodate the coupler.

4. A locomotive bumper construction comprising a bumper beam, a coupler pocket in front of the beam, and a pilot below the pocket having side members rising therefrom, one to either side of the pocket, the pilot being constructed to present a V-front and the side members being substantially a vertical continuation thereof.

5. A locomotive bumper construction comprising a bumper beam, a coupler pocket in front of the beam, and a pilot below the pocket having side members rising therefrom, one to either side of the pocket, the pilot being constructed to present a V-front and the side members being substantially a vertical continuation thereof, together with means for securing the side members to the beam.

6. A locomotive bumper construction comprising a bumper beam, a coupler pocket in front of the beam, and a pilot below the pocket having side members rising therefrom, one to either side of the pocket, the pilot being constructed to present a V-front and the side members being substantially a vertical continuation thereof, and the pocket a V-shaped portion bridging the space between the side members.

7. A locomotive bumper construction comprising a bumper beam, and a pilot at the front of and secured to the beam of substantially U-shape in vertical section and presenting forwardly converging side surfaces. 40

8. A locomotive bumper construction comprising a bumper beam, and a pilot at the front of and secured to the beam of substantially U-shape in vertical section and presenting forwardly converging side surfaces, together with a coupler pocket between the legs of the U. 45

9. A locomotive bumper construction comprising a bumper beam, and a pilot and coupler pocket in advance thereof adapted to present V-shaped surfaces above and below the coupler, the apices of which are substantially vertically in line with the coupler head. 50

10. A locomotive bumper device having a V-front with a coupler receiving recess in the front thereof, and a coupler having its head in substantial vertical alignment with the apex of the V. 55

11. In a locomotive, a pilot and a coupler constructed to present a V-shaped forward face adapted to enshroud the coupler.

12. In a locomotive, a pilot having a base portion and a pair of spaced side portions rising therefrom, and a coupler pocket member in the space between the side portions, all so constructed as to present a V-shaped forward face adapted to enshroud the coupler. 65

In testimony whereof, I have hereunto signed my name. 70

WILLIAM E. WOODARD.
